CORE DRILL

Benjamin F. Blanchard, Brea, Calif., assignor to
 Union Oil Company of California, Los Angeles, Calif., a corporation of California

Application July 5, 1932, Serial No. 620,833

17 Claims. (Cl. 255—72)

This invention relates to core drills which are commonly employed for taking core samples of the earth's structure when being penetrated in connection with the drilling of oil wells and the like.

In one type of core drill a barrel which is movable with respect to the outer housing is employed for reception of the core, such inner core barrel being sometimes so mounted as to actuate core gripping dogs or jaws when it is desired to break off the core. An object of the present invention is to mount such a core barrel so that it may be held in an elevated position during drilling to permit proper retraction of the core breaking jaws and to permit depression when desired to actuate the core breaking jaws into operative position. A further object is to insure against twisting off the core before cutting of the core has been completed.

Primarily the invention resides in a combination of a movable core barrel and core breaking means with a piston adapted to be actuated by the pressure of mud or other drilling fluid which is commonly circulated through the drill stem which carries the core bit. The function of this mud circulation is the proper lubrication and cooling of the drill bit and elevation and discharge of the cuttings from the well hole. In a preferred form the invention includes a spring partly counterbalancing the weight of the core barrel so that the pressure of the circulating mud is relied upon only in part to maintain elevation of the barrel during core drilling. The invention also includes such a combination wherein the core barrel is rotatably mounted with respect to the housing for the core barrel, and if desired with respect to the piston also. For purpose of providing a differential of pressure between the two sides of the piston, the under side of the piston is connected to receive the full applied pressure of the mud passing downward through the drill stem, and the upper side of the piston is connected with the exterior of the drill stem so that only the hydrostatic head is exerted thereon.

In the accompanying drawing wherein one embodiment of the invention is disclosed by way of illustration:

Fig. 1 is a vertical section through a core drill constructed according to the present invention and taken approximately on the line 1—1 of Fig. 2; and

Figs. 2, 3, 4 and 5 are cross sections taken respectively upon the lines 2—2, 3—3, 4—4, 5—5 of Fig. 1.

According to the form illustrated in the draw-

ing a drill stem 10 is threadedly connected with an upper tubular housing element 12 which in turn is threadedly connected by means of a tool joint 14 with a lower housing element 15. The element 15 has the usual or any preferred type of core bit 16 threadedly mounted thereon. The housing 15 receives a core barrel 18 whose lower end may be beveled as shown for the purpose of engaging an annular series of core breaking dogs or jaws 20 and forcing the same inward so that they may grip a core and cause the same to be broken off as hereinafter indicated. In the form shown these jaws 20 are pivoted in a carrier 22 which may be threaded into the bit 16 and securely retained to such position by engagement of the lower end of the housing member 15 which is threaded down into said bit 16. The jaws 20 and carrier 22 also serve as a core catcher and retainer when the core has been broken off. As shown, the lower end of core barrel 18 slidably projects into the upper end of the carrier 22 and the sliding joint therebetween may be packed for the exclusion of mud as indicated. The upper end of core barrel 18 is closed by a head 24 carrying at its upper end a cage 25 containing a ball check valve 26 when desired. A rod 30 extends upward from the cage 25 through a perforated positioning disk or spider 32 whose perforations 33 permit passage of mud. The upper end of the rod 30 is connected with the lower end of a bearing retainer 34 which contains a ball bearing unit 35. A piston rod 36 which is journaled in bearing 35 projects upwardly through the retainer 34 and carries on its upper end a piston 38 adapted to reciprocate in a cylinder 40. The rods 30 and 36 thus constitute a divided piston rod whose parts are connected by a rotary joint 34, 35 which does not affect the functioning of piston 38. The cylinder 40 is secured to the wall of the housing 12 through the medium of suitable spacing lugs 42 which are integral with the cylinder and are preferably welded to the wall 12 as indicated at 44. In this manner channels 45 are provided between cylinder 40 and the wall of member 12 which serve to pass mud downward from the drill stem 10. The cylinder 40 is open at its lower end in order that the full mud pressure may be exerted on the under side of the piston 38, but the upper end of cylinder 40 is closed to the mud stream as shown. However the small chamber 46 in said upper end of the cylinder is connected with the exterior of the housing member 12 through the medium of a small tube 48 through which the hydrostatic head in the well outside the drill stem is transmitted to the upper side of said piston.

In order to assist the mud pressure in elevating the piston 38 a spring 50 is disposed about the rod 30 in a position between the bearing retainer 34 and the spacer or spider 32. To provide a satisfactory abutment for the lower end of said spring 50 a suitable ball bearing 52 is mounted upon the spider 32. If required a thrust bearing 54 of suitable type may be provided on rod 30 between cage 25 and spider 32.

10 In operating with this structure, the core drill 16 is rotated from the surface of the well through the medium of the drill stem 10 and the usual drilling mud is circulated downward through the bore of said drill stem, past the cylinder 40 through the mud channels 45, and thence through the apertures 33 of the spider 32 into the chamber around the core barrel 18. From this chamber the mud is directed downward into the vicinity of the cutting blades of the bit 16 by way of discharge passages 55 provided in the lower end of the housing member 15, or by way of any other form of passage suitably located to discharge the mud into the vicinity of the bit to clear and cool the latter in substantially the usual manner of operating devices of this general character. The mud head of course rises in the well hole and overflows at the surface to discharge the cuttings. The differential of pressure between the combined head and pump pressure exerted upon 25 the under side of the piston 38, and the lower outside head pressure exerted through the connecting tube 48 upon the top of the piston, taken in conjunction with the expansive energy of the spring 50, serves to maintain the piston 38 and the core barrel 18 in elevated position, so that the lower edge of barrel 18 is lifted out of engagement with the core gripping dogs 20.

As the bit 16 rotates it cuts a core which moves gradually upward into the core barrel 18 past the 40 dogs 20 and tends to force the trapped mud upward past the ball check valve 26. This core, being still integral with the rock formation at the bottom of the hole, exerts considerable friction upon the inner walls of the core barrel 18 tending to prevent the relative rotation of said core barrel 18 with respect to the housing 15. Where this difficulty is not overcome there is a further tendency to twist off the core instead of allowing it to remain intact. This difficulty however is 45 overcome by reason of the rotary joint provided between the rods 30 and 36 by the bearing 34, 35 which permits relative rotation between these parts. This rotation is also facilitated by the ball bearing structure at 52, and of course the rod 50 30 rotates freely in the central hub of spider 32. The lower end of core barrel 18 also rotates freely in the packed extension of the carrier 22. In this manner during drilling there is no interference with the functioning of the piston 38 which is 55 maintained in elevated position under the influence of the mud pressure and may remain in relatively stationary or non-rotative relation with respect to the rotating drill stem 10 and the housing 12.

60 When a core has been cut sufficiently long to fill the barrel 18, the pump pressure on the circulating mud is cut off with the result that the pressures above and below the piston 38 are equalized. Possibly, if the core barrel 18 and associated parts are heavy enough, they will settle somewhat against the spring 50 thus causing the beveled lower edge of the core barrel 18 to engage the upper ends of the core breaking jaws 20 and swing them into engagement with the 65 walls of the core. Or, if the core barrel does not

settle by gravity, elevation of the whole structure through the medium of the drill stem 10 will result in the exertion of longitudinal friction between the core and the core barrel sufficient to move the core barrel 18 downward with respect to the housing 15 and the jaws 20 as the latter are elevated, with the result that the beveled lower edge of the core barrel 18 positively forces the jaws 20 into engagement with the sides of the core. Further elevation of the structure forces 10 said jaws into the core until the core is broken off at the point where the jaws penetrate. The core will then settle down upon the jaws forcing them into a horizontal position, and as a consequence said jaws together with the carrier 22 15 act as a core catcher which supports the core and retains it within the barrel 18 until elevated to the surface of the well.

From the foregoing it will be apparent that the present structure makes it possible to rely upon 20 the pressure of the circulated mud as a medium for maintaining elevation of a core barrel in an uppermost position during core drilling and for actuation of the core barrel into a lowermost position for core breaking purposes when desired 25 to recover the core, the latter function being accomplished simply by removal of pump pressure from the mud. At the same time the present invention permits relative rotation of the core barrel with respect to the drill stem without 30 any interference with the functioning of the piston and while maintaining elevation of the core barrel.

It is to be understood that the present disclosure is merely illustrative of the generic invention, and that many variations within the skill of the average mechanic may be developed which will fall within the range of the appended 35 claims.

I claim:

1. A core drill comprising a rotatable housing carrying a core bit on its lower end, a core breaker and catcher positioned within the bit adjacent its lower end, a core barrel cooperating with said breaker and catcher to receive a core, a piston connected with said core barrel, a cylinder carried by said housing and receiving said piston, said housing and cylinder having means for transmitting circulated mud pressure to one end of the cylinder for maintaining the piston and core barrel in an elevated position.

2. A structure according to claim 1 and a pressure transmitting connection extending between the cylinder on the other side of the piston and the exterior of said housing.

3. A structure according to claim 1 wherein a rod connects the piston and core barrel and the rod is divided and a rotatable joint interposed therein.

4. A core drill comprising a rotatable drill stem, a housing carried thereby, a core bit carried by said housing, a core barrel mounted within the housing, and a piston carried by the core barrel and adapted to be moved to elevated position under influence of fluid pressure supplied to said housing.

5. A structure according to claim 4 wherein a core breaker is carried by the housing and is actuatable through the medium of the core barrel.

6. A structure according to claim 4 wherein a 70 rotatable joint connects the piston with the core barrel to permit relative rotation.

7. A structure according to claim 4 wherein a spring is associated with said piston to assist maintaining its elevation.

8. A structure according to claim 1 wherein a spring is associated with the piston to assist in maintaining its elevation.
9. A structure according to claim 4 wherein a rod connects the piston with the core barrel, a rotatable joint interposed with said rod and a spring connected with said rod to assist the piston in maintaining the core barrel in elevated position.
10. 10. A core drill comprising a housing adapted for the circulation of fluid under pressure therethrough, a core bit carried by the lower end of said housing, a core barrel disposed within said housing, a cylinder provided in said housing and a piston mounted within said cylinder and connected with said core barrel, said piston being positioned to receive the pressure of the circulated fluid on one side and being adapted to be moved into elevated position under the influence of said pressure.
11. A structure according to claim 10 and a connection between the cylinder at the other side of the piston and the exterior of the housing.
12. A structure according to claim 10 wherein a core breaker is carried in the housing and is actuatable through the agency of the core barrel.
13. A structure according to claim 10 and a rotatable joint between the piston and the core barrel permitting relative rotation between the piston and the core barrel.
14. A core drill comprising a housing, a core barrel reciprocably mounted therein, a core breaker associated with said barrel and actuatable thereby when in a lower position, means for sup-
- plying a fluid under pressure to the housing, and means connected with the core barrel and actuatable by said fluid pressure to elevate the core barrel.
15. A core drill comprising a housing, a core barrel mounted within the housing, a core breaker in the housing, a cylinder within the housing, a piston associated with the core breaker and movably mounted in said cylinder, means associated with the piston for actuation of the core breaker to breaking position, means connecting one side of the piston with the exterior of the housing, and means to supply fluid under pressure to the other side of the piston to move said piston for operation of the means for actuating the core breaker.
16. A structure according to claim 15 wherein the housing contains a passage through which the pressure fluid is conducted downward therethrough to supply the drill and the piston.
17. A core drill comprising a housing, a core barrel mounted therewithin, a core breaker associated with said core barrel, a piston directly connected with said core barrel, a cylinder receiving said piston and mounted within said housing, means in said housing connecting one side of the piston with the exterior of the housing and the other side of said piston with the interior of the housing for transmission of corresponding pressures, and means to supply fluid pressure to the piston to maintain the piston and core barrel in predetermined position with respect to the core breaker.

BENJAMIN F. BLANCHARD.
